Inventor: Howard Lyon by Delos Holden his Atty.

UNITED STATES PATENT OFFICE.

HOWARD LYON, OF GLOUCESTER CITY, NEW JERSEY, ASSIGNOR TO WELSBACH LIGHT COMPANY, A CORPORATION OF NEW JERSEY.

IGNITION APPARATUS.

1,118,941.

Specification of Letters Patent.

Patented Dec. 1, 1914.

Application filed June 11, 1910. Serial No. 566,408.

To all whom it may concern:

Be it known that I, HOWARD LYON, a citizen of the United States, residing at Gloucester City, in the county of Camden and State 5 of New Jersey, have invented certain new and useful Improvements in Ignition Apparatus, of which the following is a description.

My invention relates to a novel means 10 for igniting a jet or current of combustible gas, for example, ordinary illuminating gas, gasolene, etc., all of which are hereinafter referred to simply as gas.

The invention is a modification of a novel 15 apparatus disclosed and broadly claimed in my application Serial No. 541,600 filed February 2, 1910.

In order that the invention may be more 20 fully understood reference is hereby made to the accompanying drawing of which—

Figure 1 is a side elevation, partly in section, showing my improved apparatus applied to a well known form of inverted incandescent gas burner. Fig. 2 is an enlarged longitudinal section of the ignition tube of Fig. 1. Fig. 3 is a side elevation 25 of the same, partly in section, in a plane at right angles to the plane of Fig. 2. Fig. 4 is a section on line 4—4 of Fig. 1, and Fig. 30 5 is a bottom plan of Fig. 4.

The gas burner of Fig. 1 comprises an inverted U-shaped supply tube *a*, provided with the usual gas check *b*, air inlets *c*, flash diaphragm *d*, globe holder *e*, Bunsen tube 35 *f*, and mantle holder *g*. The globe holder *e* is in the form of a canopy or inverted funnel having large openings *h* for discharging the heated products of combustion. Near the center of the globe holder and at 40 substantially the highest point is an opening 1 above which is mounted a nipple 2 having a flange 3 which is secured by rivets (not shown) to the canopy *e*, the bore of said nipple registering with said opening. 45 Upon the nipple 2 is mounted a vertical tube 4 secured by a set screw 5. The bore or interior of said tube forms an ignition chamber. The walls of the tube 4 are cut away intermediate its ends forming two large 50 rectangular openings or windows 6 and 7. At the bottom of these openings is a baffle plate 8 extending across the bore of the tube and composed preferably of some non-oxidizing substance such as Monel metal 55 which does not scale and is well adapted for

the purpose, its composition being approximately 74 to 75% nickel, 24 to 25% copper, 1 to 2% iron. The upper end of the tube 4 is closed by a plug composed of a metal sleeve 9 secured by a set screw 10, and an insulating bushing 11 set therein and through which passes a headed conducting bolt 12 secured by a nut 13. This nut has a passage 14 for receiving a conducting wire 15 and a set screw 30 for securing the same. A 60 very fine wire or filament 16 of platinum or platinum alloy is secured at its ends to the supporting conductors 17 and 18, one of which is soldered to the head of the bolt 12 and the other to the sleeve 9. The wire 65 or filament 16 is straight, and extends horizontally across the axis of the tube 4 and parallel to the edges of the baffle plate 8 and to the planes of the openings 6 and 7. The width of said openings is preferably 70 somewhat greater than the length of the wire 16. By reason of the arrangement 75 of these openings with respect to said wire and their considerable width, there is a very thorough exposure of the wire to the action of atmospheric air. The gas controlling cock may be of any desired form, but is preferably constructed so as to simultaneously admit gas to the pipe *a* and complete an electrical circuit through the wire 80 85 15. As shown it comprises a body 21 having the usual key 22, from which depends a pin 23 of insulating material. There is a ring 24 of insulating material mounted on the body 21, and a conducting ring 25 on 90 said ring 24. Springs 26 and 27 are secured to said ring 25 by screws 28 and 29, the latter of which acts as a binding post for a wire connected to one pole of an electric battery, one dry cell being 95 sufficient for the purpose. The other pole of the battery is grounded or connected to the gas supply pipe. The free end of the spring 26 extends outwardly in position to be engaged by the pin 23. An insulating 100 block 40 is secured to the body 21 by a screw 31, and a contact 32 is mounted thereon in position to be engaged by the spring 27. A binding post 33 secures the wire 15 to said contact 32. 105

The device operates as follows: The key 22 of the cock 21 is turned so as to admit gas to the pipe *a* and to simultaneously complete an electrical circuit from a battery or cell through the ring 25, spring 27, contact 110

32, wire 15, bolt 12, wires 17, 16 and 18, sleeve 9 and tube 4 to the ground and back to the battery. The gas which is admitted to the lamp flows from the burner head of 5 the Bunsen tube *f*. The stream of gas rises into the top of the canopy 2 and a portion of it flows through the opening 1 into the ignition chamber within the tube 4. Passing upward around the edges of baffle plate 10 8 eddying or whirling currents of gas or gas and air mixtures are created which curl over the edges of the baffle plate and envelop the ignition wire which is freely exposed along its entire length to the atmosphere by reason of the openings 6 and 7 to the planes of 15 which it is parallel. The formation and effectiveness of these eddying currents are probably due in large part to the shape of the baffle plate and its position in the tube 20 4. The baffle plate also protects the filament against excessive temperatures during ignition due to mixtures of too great richness. The hottest portion of the filament during ignition, which may be termed its 25 active portion, is usually at and close to its center on account of the flow of heat from the filament to the leading in wires or supporting conductors 17 and 18. The width of the baffle is substantially greater than 30 that of the active portion of the filament, whereby the filament and particularly its active portion is protected against excessive temperatures during ignition, by reason of the fact that the baffle is so placed as to permit only a small percentage of the ascending 35 gas to approach the filament and at the same time to permit the free access thereto of atmospheric air entering through the windows 6 and 7. The baffle together with 40 said windows produce an ignitable mixture of minimum richness. The electric current which is at that time passing through the said wire is preferably of a strength which is insufficient of itself to heat the wire to 45 the kindling temperature of the gas, but is sufficient to initiate catalytic action of the gas upon the said wire, one dry cell being sufficient for the purpose. The catalytic action quickly brings the wire to the kindling 50 temperature of the gas, whereupon the gas is ignited and the flame immediately consumes all of the gas in the lamp and thereafter burns at the burner head of the Bunsen tube *f* in the usual manner. Obviously, 55 the flame thus established consumes all of the gas issuing from the burner head and thereby automatically cuts off all gas from the ignition tube. The heated products of combustion pass out of the lamp in the 60 usual manner through one or more openings *h*, only a small portion passing through the opening 1 into the ignition device from which they escape through the openings 6 and 7. The baffle plate in conjunction with 65 the narrow side pieces cause the products of

combustion to form eddy or whirling currents which draw in air and envelop the wire as long as the gas is burning. These currents appear to revivify or energize the platinum making it more sensitive to the 70 catalytic action hereinbefore referred to. Moreover, eddy currents of mixed gases are formed about the wire prior to ignition and these currents prevent a condition of "hanging fire," thus making the ignition more 75 prompt and shielding the wire at a moment of intense activity from prolonged strain. After the lamp is ignited the key 22 is released and the spring 26 thereupon moves the same back sufficiently to open the electric circuit as shown in Figs. 4 and 5.

Having now described my invention, what I claim is:

1. An igniter having an ignition chamber, a baffle plate within the same, the surface of 85 which opposite the filament at its lateral edge or edges is substantially flat, and a conducting filament situated adjacent said baffle plate, the width of said baffle plate being substantially greater than that of the active 90 portion of said filament, substantially as set forth.

2. An igniter having an ignition chamber, a substantially flat, transverse plate within the same, and a conducting filament situated 95 adjacent said plate, the width of said baffle plate being substantially greater than that of the active portion of said filament, substantially as set forth.

3. In a gas lamp, an ignition tube, a filament therein, means for applying an electric current thereto, a substantially flat plate within the bore of said tube and transverse to its axis, said plate having a lateral edge extending in a straight line, and said plate 100 being placed adjacent said filament and between it and the gas supply, substantially as set forth.

4. In a gas lamp, an ignition chamber, a filament therein, means for applying an 110 electric current thereto, a baffle between said filament and the gas supply, and an opening or window in said chamber opening directly to the atmosphere, said filament extending in the same general direction as the plane of 115 said opening and adjacent the same, substantially as set forth.

5. In a gas lamp, a gas supply having an outlet, an adjacent chamber having an inlet in the path of gas issuing from said outlet, 120 a horizontal filament within said chamber, a horizontal baffle plate below the same and an opening or window in said chamber opening directly to the atmosphere, said filament extending in the same general direction as the 125 plane of said opening and adjacent the same, substantially as set forth.

6. An ignition tube, a baffle plate within the same, an opening or window formed in the wall of said tube adjacent said baffle 130

plate, and a conducting filament situated above said baffle plate and extending in the same general direction as the plane of said opening.

5 7. In a gas lamp, an ignition chamber having oppositely disposed openings or windows opening directly to the atmosphere, a baffle plate adjacent said windows and extending in the same general direction as the 10 planes thereof, and a conducting filament situated above said baffle plate, substantially as set forth.

8. In a gas lamp, an ignition chamber having oppositely disposed openings or windows opening directly to the atmosphere, a baffle plate located at the lower edges of 15 said openings and extending in the same general direction as the planes of said openings, and a conducting filament situated immediately above said baffle plate, substantially as set forth.

9. An ignition tube having oppositely disposed openings whose width is substantially equal to the bore of the tube, a transverse 25 member within said tube at the base of said openings and of a smaller area than said bore, and a filament above said transverse member.

10. In a gas lamp, an ignition chamber, a baffle within the same, a filament adjacent 30 the baffle and a window adjacent and substantially parallel to said filament and opening directly to the atmosphere, the width of the window exceeding the length of the filament, substantially as set forth.

11. An ignition tube the lower end of 40 which is open to form an inlet, a transverse conducting filament mounted therein, a window in said tube adjacent and substantially parallel to said filament, the width of the window exceeding the length of the filament.

12. A burner head, an ignition chamber having an inlet in the path of gas issuing from said burner head, an ignition filament 45 within said chamber, and a substantially flat baffle plate close to said filament, and between it and said burner head, the width of said baffle plate being substantially greater

than that of the active portion of the filament whereby the latter is protected against 50 excessive temperatures during ignition.

13. A burner head, an ignition chamber having an inlet in the path of gas issuing from said burner head, an ignition filament within said chamber, one or more air inlets 55 adjacent said filament opening directly to the atmosphere, and a substantially flat baffle plate close to said filament and between it and said burner head.

14. In a gas lamp, a gas supply having 60 an outlet, an ignition chamber having an inlet in the path of gas issuing from said outlet, an ignition filament within said chamber, and a baffle between said filament and said gas outlet, and adjacent said filament, 65 and having a substantially flat surface adjacent the filament, substantially as set forth.

15. In a gas lamp, a gas supply having an outlet, an ignition chamber having an inlet in the path of gas issuing from said outlet, 70 an ignition filament within said chamber, and a baffle between said filament and said gas outlet and adjacent said filament, the surface of said baffle nearest the gas inlet being substantially flat, substantially as set 75 forth.

16. An igniter having an ignition chamber, a filament therein, means for applying electric current thereto, and a substantially flat transverse plate adjacent the filament 80 and between it and the gas supply, substantially as set forth.

17. An igniter having an ignition chamber, a substantially flat plate within the same, an opening or window formed in the 85 wall thereof adjacent said plate, and a conducting filament above said plate, said plate being situated adjacent the filament and between it and the gas supply, substantially as set forth.

90 This specification signed and witnessed this 4th day of June 1910.

HOWARD LYON.
